UNITED STATES PATENT OFFICE.

WILLIAM WILLIAMSON, OF SAGINAW, MICHIGAN.

EXTENSION-LADDER.

No. 873,110.

Specification of Letters Patent.

Patented Dec. 10, 1907.

Application filed April 26, 1906. Serial No. 313,813.

To all whom it may concern:

Be it known that I, WILLIAM WILLIAMSON, a citizen of the United States, residing at Saginaw, in the county of Saginaw and State 5 of Michigan, have invented certain new and useful Improvements in Extension-Ladders; and I do hereby declare the following to be a full, clear, and exact description of the invention, such as will enable others skilled in the 10 art to which it appertains to make and use the same.

My invention relates to an extension ladder and I have herein illustrated one embodiment of which my invention is susceptible.

15 One object of my invention is to provide a novel form of ladder over those heretofore noted, capable of extension and contraction, one of the novel features residing in the fact that the ladder sections are separable from 20 each other by moving the extension section downwardly.

Another important object of my invention is the provision of means adapted to operate as a reinforcing guide strip for the base section 25 of the ladder, such strip performing many important functions such as preventing side sway of the ladder when in use, strengthening the ladder considerably and preventing the splitting of any cross grain 30 timber in the base section.

Still another object of my invention is the provision of an improved means for effecting the raising and lowering of the extension section, such means comprising a peculiar fastening means to which a flexible connection 35 is removably secured.

Another object of my invention is the provision of means carried by the extension section and actuated by a rolling round, on the 40 extension section, said means adapted to take over the rounds of the stationary or base section to adjustably support the extension section at any desired height.

To these and other ends, my invention 45 consists in certain novel features and combinations of parts, together with their equivalents, such as will be more fully disclosed hereinafter and particularly pointed out in the claims.

50 In the accompanying drawings illustrating one embodiment of my invention, Figure 1 is a front view of one form of my invention when used as an extension ladder, Fig. 2 is a detail perspective view of the lower end of the 55 extension section, Fig. 3 is a vertical sectional view on line x—x of Fig. 1, Fig. 4 is a detail

view of the fingers engaged by the flexible connection, and Fig. 5 is a detail side view of one of the latches and its coöperating parts.

Referring to the drawings, A indicates the 60 base section and B the extension section of a ladder constructed in accordance with my invention. The foot of the base section may be spread as shown, although this is not a necessary incident of my device.

65

I preferably secure reinforcing guide strips 1, 1, to the rails of the base section, as shown, which strips not only operate to prevent side sway of the ladder and greatly strengthen the same, but also prevent the breaking of 70 the rails in case of cross grain timber or knots as well as preventing the splitting of the rails. Furthermore, the strips whose importance cannot be exaggerated, are arranged to lap over or overhang the inner 75 faces of the rails for a purpose hereinafter set forth.

Brackets 3, 3, are secured to the inner faces of the rails of the base section, such brackets being each provided with an extension 4, from which projects a pin 5, the pins 80 projecting toward each other from the opposite rails. The pins 5, 5, may be headed or not, as convenient.

The extension section is preferably narrower than the base section and overlies the face thereof.

The pins 5, 5, project over the rails of the extension section whereby the latter is securely held against lateral movement away 90 from the base section.

As one means for supporting the extension section at varying elevations I preferably provide the following mechanism. The lower round 13 of the extension section is 95 rotatably journaled in the side rails as by means of the pintles 14, 14, received in bearings 15, in the side rails, the pintles being of less diameter than the round whereby to prevent a longitudinal movement thereof. At 100 opposite ends of the round 13, I secure the sleeves 16, 16, from which project the arms 17, 17, having the studs 18, 18, located at the upper free ends, the studs extending in opposite directions. A double latch 19, of A 105 shape in general formation is pivotally secured at its apex to the inner face of each rail of the extension section, at a point between the round 13 and the round next above, the latches each being suitably braced as at 110

20, 20, the braces having slots 21, 21, formed therein in which are loosely received the

stud 18, 18. The opposite lower ends 21, 21, of the latches are adapted to engage the rotatable round 13 and a round of the base section as shown in the drawings whereby to support the extensible section in any position within its limit of movement. I prefer to secure sockets 30, 30, to the inner faces of the rails of the adjustable section, the sockets adapted to receive the apices of the latches and assisting in the support of the weight of the adjustable section and the operator thereon, the pivot pin passing through the socket and latch. Ordinarily this means of adjusting the extensible section is sufficient since an operator accustomed to such structures can mount the base section pushing the extensible section before him from time to time, the bosses or rolls 11 or 12 engaging the wall and reducing the friction without marring the surface, but for convenience of others and to facilitate the use of the device, I prefer to equip the rotatable round 13 with a pair of suitably curved fingers 22, 22, the fingers being curved in opposite directions as shown and adapted to engage and hold a flexible connection 23, which connection may have a knot or other enlargement 24 formed intermediate its ends and caught in the fingers. The plies of the connection pass upward on opposite sides of the rotatable round and thence between the rounds of the extension and base sections respectively thence over a double block or pulley 25 secured to the upper round of the base section from whence the ends depend in position to be grasped by the operator. A pull on either end of the connection will operate to raise the extensible section, strain on one ply being adapted to rock the rotatable round in one direction to move the inner lip of the latch away from the rounds of the base section, and pull on the remaining ply operating to rock the round in the opposite direction and cause the inner lip of the latch to overhang the rounds of the base section. Thus it will be seen that in operating the ladder a downward pull can be given both plies of cord until the latches have cleared the round on the base section over which their inner lips have caught, whereupon the weight of the extension section may be supported for an instant on one of the plies alone thereby rocking the round and catches as set forth to prevent the inner lips from engaging the rounds of the base section after which the extensible section may be raised or lowered and when in its adjusted position, a preponderance of strain is applied to the other ply whereby to rock the latch in the opposite direction and cause its lip to engage the adjacent round of the base section. In this manner, the extensible section need not be lowered below the point at which it is to be adjusted nor need it be raised above the base round on which it is to be supported only

sufficiently to permit the lip to clear the round, and in this connection I would state that the rounds of the base and extensible sections are so arranged that they lie opposite each other to afford a broad support for the feet, rather than alternating with each other. Furthermore, the flexible connection can be instantaneously removed from the ladder and need not be used.

The extensible section is removable from either end of the base section, that is to say, it can be run up so that the foot of the extensible section leaves the head of the base section or the extensible section can be drawn downwardly until its head clears the inwardly projecting pins 5, 5 which latter mode is much easier to accomplish. It will also be observed that the latches are double, that is to say, each latch has two depending lips, one object of which is to provide a stop for the latch when its inner lip is caught over a round on the base section, the outer lip taking against the sleeve 16, to limit the inward movement of the latch and also when the latch is removed from its engagement with a round on the base section, the inner lip engages the sleeve 16 to limit the outward movement of the latch. Another result attained by this construction is to permit the extensible section to be reversed in case it becomes warped or sprung, or for any other reason. The reinforcing strips 1, 1, operate to prevent the springing or warping of the base section.

While I have shown but two sections of an extension ladder, it is plain that more might be used, a plurality of adjustable sections being successively arranged relative to each other.

From the foregoing, it is obvious that I have devised a novel construction which is both simple and efficient and one which can be placed on the market at a comparatively slight cost.

It is also evident that many changes might be made in the form and arrangement of the several parts described without departing from the spirit and scope of my invention, hence I do not wish to limit myself to the exact construction herein set forth.

Having thus fully disclosed my invention, what I claim as new, is:—

1. The combination with a base section and an extensible section, of a rocking round on the extensible section, double latches pivotally secured to the extensible section, and arms projecting from the round and positively engaging the respective latches to swing the latter toward and from the rounds of the base section, the latches adapted to take over the rounds of the base section to sustain the extensible section in adjusted position.

2. The combination with a base section and an extensible section, of a rocking round on the extensible section, double latches piv-

totally secured to the extensible section, the latches being apertured, arms projecting from the round, studs carried by the arms and receivable in the apertures in the latches 5 to positively swing the latches toward and from the rounds of the base section.

3. The combination with a base section and an extensible section slidable relative to the base section, of a rocking round on the 10 extensible section, double latches pivotally secured to the extensible section, arms projecting from the round and positively engaging the respective latches to swing the latter toward or from the rounds of the base section, 15 the latches adapted to take over the rounds of the base section to sustain the extensible section in adjusted position, oppositely extending curved fingers on the rocking round and a flexible connection having an enlargement 20 in the bight thereof, for engaging the fingers.

4. An extension ladder comprising base and adjustable sections, latches pivotally supported by the adjustable section for supporting the latter at various points relative 25 to the base section, a rocking rung, means

connecting the rung and latches, oppositely curved fingers mounted on the rocking rung and a knotted flexible connection independent of the means connecting the rung and latches for actuating the rung in opposite directions, the knot being releasably held by the curved fingers. 30

5. An extension ladder comprising base and extensible sections, a latch on the extensible section for supporting the same at various heights relative to the base section, a rocking rung, means connecting the rung and latch, curved fingers mounted on the rung and a flexible connection independent of the 35 means connecting the rung and latch, and an enlargement located intermediate the ends of the connection, the enlargement being releasably caught in the curved fingers to rock the rung in opposite directions. 40

In testimony whereof, I affix my signature in presence of two witnesses.

WILLIAM WILLIAMSON.
